United States Patent Office

Des. 187,823
Patented May 3, 1960

187,823

AIRCRAFT

Walter T. Gassaway, Sacramento, Calif.

Application November 30, 1956, Serial No. 44,015

Term of patent 14 years

(Cl. D71—1)

Figure 1 is an upper front perspective view of an aircraft showing my new design;

Figure 2 is a lower rear perspective view; and
Figure 3 is a front elevational view thereof.

I claim:

The ornamental design for an aircraft, as shown.
